US00D562878S

(12) **United States Design Patent** (10) **Patent No.:** **US D562,878 S**
(45) **Date of Patent:** **** Feb. 26, 2008**

(54) **TRUMPET COMPONENT**

(75) Inventors: **Sheryl Laukat**, Sandy, UT (US); **Tewis Laukat**, Sandy, UT (US)

(73) Assignee: **Cannonball Musical Instruments**,
Sandy, UT (US)

(**) Term: **14 Years**

(21) Appl. No.: **29/219,452**

(22) Filed: **Dec. 16, 2004**

(51) **LOC (8) Cl.** **17-02**

(52) **U.S. Cl.** **D17/10**

(58) **Field of Classification Search** **D17/10, D17/11, 13; D21/411; 84/380 R, 385 R, 84/388, 735, 741-743**

See application file for complete search history.

Primary Examiner—Adir Aronovich

(74) *Attorney, Agent, or Firm*—Advantia Law Group;
Michael W. Starkweather; Jason P. Webb

(57) **CLAIM**

The ornamental design for the trumpet component, as shown and described.

DESCRIPTION

FIG. 1 is a bottom perspective view of a trumpet component showing our design;

FIG. 2 is a reduced front view of the trumpet component attached to a return side of a lead pipe of a trumpet;

FIG. 3 is a front view of the trumpet component;

FIG. 4 is a top plan view of the trumpet component;

FIG. 5 is a bottom plan view of the trumpet component;

FIG. 6 is a right side view of the trumpet component; and, FIG. 7 is a left side view of the trumpet component.

The broken line showing of an outline and contour of a trumpet is included for the illustration only and forms no part of the claimed design.

1 Claim, 5 Drawing Sheets
